Primary Examiner—Wallace R. Burke

Assistant Examiner—Melody Brown

[57]

CLAIM

The ornamental design for a bicycle shroud, as shown.

DESCRIPTION

FIG. 1 is a left, front perspective view of a bicycle shroud showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

FIG. 1

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 345,325
DATED : March 22, 1994
INVENTOR(S) : David K. Camfield et al.

It is certified that error appears in the above-identified patent and that said Letters Patent is hereby corrected as shown below:

ON THE TITLE PAGE

insert the following: Item [73]
--Assignee: Roadmaster Corporation, Olney, Illinois--

In column 2, after "Assistant Examiner-Melody Brown"
insert --Attorney, Agent, or Firm-Willian Brinks Hofer Gilson
& Lione--.

Signed and Sealed this
Thirty-first Day of January, 1995

Attest:

BRUCE LEHMAN
